UNITED STATES PATENT OFFICE.

GEORGE W. WEBER, OF ST. PAUL, MINNESOTA, ASSIGNOR TO AMERICAN CAN COMPANY,
OF NEW YORK, N. Y., A CORPORATION OF NEW JERSEY.

PROCESS OF CANNING ASPARAGUS.

1,083,311.

Specification of Letters Patent.

Patented Jan. 6, 1914.

Application filed March 31, 1913. Serial No. 757,847.

To all whom it may concern:

Be it known that I, GEORGE W. WEBER, a citizen of the United States, residing in St. Paul, in the county of Ramsey and State 5 of Minnesota, have invented a new and useful Improvement in Processes of Canning Asparagus, of which the following is a specification.

This invention relates to improvements in 10 process of canning asparagus and other food stuffs which, of necessity, must be so packed and held within the can or container that the same cannot move around and thereby become mashed or injured during shipment.

15 The object of the invention is to provide a process of canning asparagus and other food stuffs, in which cans of the so-called "sanitary" type may be used; in which the cross sectional shape will be changed and the cross 20 sectional area decreased after the can has been filled and sealed to thereby firmly clamp and hold the food products in position within the can; and in which certain or pre-determined areas or portions of the sides of 25 the cans will be collapsed to cause the changes of cross sectional shape and area.

The invention furthermore consists in the 30 improvements in the steps and novel combinations of the steps of the process herein shown, described or claimed.

In the drawing forming a part of this 35 specification, Figure 1 is a perspective view of a sanitary can used in carrying out my improved process. Fig. 2 is a diametrical, longitudinal, sectional view of a can filled with asparagus, showing the can before the same is collapsed, and Fig. 3 is a longitudinal, sectional view of a can filled with asparagus, showing the can in its final or collapsed condition, in which the asparagus 40 is firmly clamped or held at the centers of the stalks and ample space provided for the tips so that the same will not be crushed.

45 As is well known, certain food products which are packed in long pieces, and particularly asparagus, must be held within the can during shipment, so that the same can neither slide up nor down within the can when the latter is tipped, and must also be prevented from rotating or moving around within the can while the same is being handled, in order to prevent the delicate asparagus tips from being in a mashed or injured condition when delivered to the consumer.

50 The consuming public is now demanding

more and more that all food products be shipped in the so-called sanitary can, that is, a can having the ends united to the body by means of seams without employing solder, and from the manufacturer's point of view, 55 the use of such sanitary cans is highly desirable, since they may be filled readily on account of the large open mouth of the can before the cover is applied, and furthermore, for the reason that the cans, being of cylindrical form, are more easily double seamed than are the square or irregular shaped cans.

In carrying out my process, I provide a sanitary can 10, which, as shown in the 60 drawing, is of cylindrical form and is provided with a plurality of beads, creases, indentations or other outlining means 11 which determine and outline a plurality of panels 12, the number of such panels on the can 65 shown in the drawing comprising five, although this number may be varied as desired. The can is next filled with the asparagus 13, or other food product, after which the can with its contents is passed 70 through a cooker or exhaust box to process the contents. This processing step will not only heat and expand the contents but will rarefy or attenuate the air in the small space 75 at the top of the can, with the result that 80 when the cover or closing end 14 is applied to the can and hermetically seamed thereto while the can and its contents are still hot, a partial vacuum will be created within the 85 can when the contents are allowed to cool. 90 While the partial vacuum is being formed within the can, the external atmospheric pressure will cause the panels 12 to collapse, as shown at 12^a, in Fig. 3, the shape and 95 area of these collapsed panels being determined by the beads 11, with the result that the cross sectional shape of the can at points intermediate its ends is changed from circular to polygonal, and the cross sectional 100 area materially decreased, so that the asparagus 13 will be compressed or clamped at the centers of the stalks, but the ends of the container above and below the beads 11 will remain intact, thus preventing crushing or 105 injuring of the asparagus tips.

110 Although I have shown and described my process as carried out with a particular type of container, yet it will be understood that other forms of containers may be used, and also that the cross sectional form and cross

sectional area may be changed by pressure other than that caused by a partial vacuum within the container after it is sealed, and I would have it understood that all variations and modifications of the process and steps of the process are contemplated as come within the scope of the claims appended hereto.

I claim:—

- 10 1. The process of canning asparagus and other food products which consists in first placing the food product in a sheet metal container and subsequently reducing the cross sectional area of the container at points intermediate its ends, to thereby grip and hold the food product and prevent the same from movement within the container, substantially as specified.
- 20 2. The process of canning asparagus and other food products, which consists in placing the food product in a sheet metal container and thereafter simultaneously decreasing the cross sectional area and changing the cross sectional shape of the container at points intermediate its ends, substantially as specified.
- 30 3. The process of canning asparagus and other food products, which consists in first taking a container of substantially uniform cross sectional area throughout its length, then filling the container with the food product, and subsequently reducing the cross sectional area of the container at points intermediate its ends, to thereby firmly grip and hold the food product within the container, substantially as specified.
- 40 4. The process of canning asparagus and other food products, which consists in first taking a container having cylindrical end portions, then filling the container with the

food product, and subsequently reducing the cross sectional area and changing the cross sectional shape of the container at points intermediate the ends of the container by pressure exerted on the side walls thereof, substantially as specified.

5. The process of canning asparagus and other food products which consists in first taking a container having cylindrical end portions, then filling the container with the food product, heating the contents of the container before the container is sealed, then sealing the container while the contents are still hot, to thereby produce a vacuum within the container when the contents have cooled sufficient to cause the side portions of the container to collapse, substantially as and for the purpose specified.

6. The process of canning asparagus and other food products, which consists in first taking a cylindrical sheet metal container, then filling the same with the food product, then sealing the container, and finally changing the cross sectional shape of the container at points intermediate its ends from circular to polygonal, substantially as specified.

7. The process of canning asparagus and other food products, which consists in providing a sheet metal container of substantially uniform cross sectional area throughout with panel outlining means, then filling the container with the food product, and thereafter collapsing the outlined panel portions, substantially as and for the purpose specified.

GEORGE W. WEBER.
